UNITED STATES PATENT OFFICE.

BENGT M. W. HANSON, OF HARTFORD, CONNECTICUT, ASSIGNOR TO PRATT & WHITNEY COMPANY, OF HARTFORD, CONNECTICUT, A CORPORATION OF NEW JERSEY.

FRICITION-CLUTCH.

No. 909,891.

Specification of Letters Patent.

Patented Jan. 19, 1909.

Application filed April 25, 1908. Serial No. 313,535.

To all whom it may concern:

Be it known that I, BENGT M. W. HANSON, a citizen of the Kingdom of Sweden, having declared my intention of becoming a citizen 5 of the United States, residing at Hartford, in the county of Hartford and State of Connecticut, have invented certain new and useful Improvements in Friction-Clutches, of which the following is a specification.

10 This invention relates to friction-clutches of that type in which a split-ring is expanded by pivoted levers against the inner wall of a device to be connected to a shaft or other support, and has for its object the 15 provision of means for actuating said pivoted levers, whereby amplified leverage is obtained, and a split-ring or other clutch-surface is forced against the complementary clutch-surface with increased power.

20 Other objects of the invention will be hereinafter set forth.

In the accompanying drawings, Figure 1 is a view partially in section and partially in side elevation showing one application 25 of the invention. Fig. 2 is a side elevation partially in section. Fig. 3 is a transverse section taken on line 3—3 of Fig. 2; Fig. 4 is a diagrammatic view illustrating the action 30 of the improvement. Figs. 5 and 6 are, respectively, end and longitudinal sectional views of a sleeve hereinafter described; the section being taken on line 6—6 of Fig. 5. Fig. 7 is a plan view of a friction-block; Fig. 8 is an enlarged side view of one of the 35 pivoted levers employed for actuating the expansion-rings, and Fig. 9 is a plan view of one of the wedge-blocks.

Like numerals designate similar parts throughout the several views.

40 Referring to the drawings, the numeral 1 designates framework of any desired kind, in bearings of which (not shown) is journaled a shaft 2 which may be either a driving or a driven shaft as circumstances may 45 require.

Pulleys 3 and 4 upon which the usual straight and crossed belts are placed are shown sleeved upon the shaft 2, each of said pulleys having at its inner side a circumferential flange designated, respectively, by 3' and 4', thus forming chambers or cups for the reception of clutching-devices hereinafter described.

Designated by 5 is a sleeve secured to the

shaft 2 by a screw 6, this sleeve being shown 55 detached from said shaft in Figs. 5 and 6, and as provided on one side with a groove 7, having a flat bottom, and on its opposite side with a flat-bottomed groove 8. Each of said grooves terminates, in a slot indicated, respectively, by 7' and 8' in Fig. 6, and in the slots and fitted upon flattened portions 2' of shaft 2 are friction-blocks 9, 9'. Each friction-block is split longitudinally at 10, and at its end adjacent the open end of 65 the slot is internally threaded at 10'.

Reduced cylindrical ends 11, and 11' are formed on the sleeve 5, and the slots 7' and 8', pass through said reduced ends, and in each slot is placed a friction-block 9, 9'. A 70 screw 12 is threaded into the seat 10 of each friction-block, and a transverse bolt 13 serves as a means for clamping the walls of the split-part of the block upon said screw.

Fitted upon the reduced end 11 of sleeve 75 5 is a split-expansion-ring 14 and a similar ring 15 is placed upon the reduced extremity 11' of said sleeve, both rings being located within the cups or circumferential, overhanging flanges 3' and 4' of the pulleys 3 80 and 4. To prevent displacement of said rings, each is grooved to receive a flat block or key 16 secured in seats of the sleeve by screws 17 (see Fig. 3).

Fitted upon the beveled head 12' of each 85 screw 12 are the grooved heads 18 of levers 19, the rear end of each head being rounded at 18' to conform to and be received in seats 20 in the opposing ends of the expansion-rings 14 and 15, and each lever having an 90 arm 19' terminating in an inclined projection 19'. Normally the expansion-rings 14 and 15 tend to contract and closely embrace the reduced ends of the sleeve 5, and it is only when a ring is expanded against either 95 the inner wall of the flange 3' or the like wall of flange 4' that a connection is made with the pulley 3 or 4 or other element which may be substituted for said pulley without departure from the invention.

100 Heretofore it has been common in the art to force a wedge or cone between the free ends of the pivoted levers and toward the fulcrum screw thereof—thus causing said levers to turn on the inner side of said screw 105 and thus to have a toggle-like expansion action upon the split-ring. In other words in the old way of actuating said pivoted

levers the cone or wedge will separate them by being driven in a direction toward their free ends in a line towards their fulcrum or pivot.

5 In the present case a reverse direction of movement is applied to the wedge or cone and it moves away from the fulcrum of the pivoted levers, and to enable this action to be carried out the inner surfaces of the heads 10 of the levers and the wedge and its carrier-block are of peculiar formation, as will be hereinafter described.

Referring to Figs. 2 and 8 it will be seen that the inner face of the head 18 of each 15 lever 19 is inclined at 18^2 , so that one end-wall 18⁴ of the groove 18⁴ is longer than the opposite end wall 18⁵ of said groove, thereby providing a longer bearing-surface on the outer side of the beveled head 12 of the fulcrum-screw than on the inner side of said 20 head for a purpose now to be described.

Designated by 21 are blocks fitted for sliding movement in the grooves 7 and 8 of the sleeve 5, and each of these blocks is provided 25 with a longitudinal rib or projection, having a narrow shank 21' terminating in an abutment 21² at one end and in a head 21³ having downwardly-inclined walls 21⁴ at its opposite end, the sides of each head being also inclined with reference to a horizontal plane 30 as at 21^5 , to prevent said block from working in toward the fulcrum.

In the inner end of each block 21 an opening 22 having internally-threaded walls is 35 formed for the reception of a screw 23. These blocks and their ribs or projections are disposed on the sleeve as indicated in Fig. 1, the inner end of each overlapping the inner end of a friction-block 9, 9'.

40 Surrounding the sleeve 5 is another sleeve 24 having a groove 24' and circumferential end flanges 24² overlapping the flanges 3', 4', of the pulleys 3 and 4.

Designated by 25 is a rock-shaft journaled 45 in the frame 1, and having a depending arm 26 equipped with a roller 27, and a yoke 28 provided with shoes 29 fitting in the groove 24' of sleeve 24. For actuating this rock-shaft any desired means may be employed 50 without departure from the invention, and I have shown for this purpose a pair of cylinders 30 and 31, closed by plugs 32, and 33 at their outer ends and preferably formed in a casting 34 secured to the under side of the 55 top of frame 1, and having an opening 35 registering with a similar opening 36 in the frame, said openings receiving the arm 26 of the rock-shaft, as illustrated in Fig. 1. In the cylinders are pistons 37 and 38 one 60 on each side of the free end of arm 26. Usual ports 39 are formed in the cylinders for the supply of motive-fluid to the cylinders, and exhaust-ports and passages controlled by valve-mechanism (not shown) will also 65 be provided.

Referring to the diagram Fig. 4 it will be seen that when either block 21 is actuated by the sleeve it will move away from the fulcrum 18 of said levers and its wedge-shaped head 21³ will be pulled between the 70 ends 19² thereof, thus rocking the levers and causing the projections 18³ of said levers to bear at approximately the points *a*—*a* on the fulcrum-screw, and giving a working-length to said levers represented by the dot-and-dash line *b*, thus conforming to the well known law that given a certain resistance the power required to overcome said resistance decreases as the length of the lever-arm increases.

As the levers rock on their fulcrum the friction-block 9 or 9', as the case may be, will yield slightly in the slot of the sleeve, thus enabling the pivotal points 18³ of the heads 18 of levers 19 to be brought into 85 alignment when the full toggle-like action of said levers is exerted on the expansion-ring, and when the levers are released the contraction of the expansion-ring will cause the friction-block to be returned to normal position, aided, if necessary, by the contact of 90 the block 21 when it moves back to normal position.

It will be apparent that my clutch involves a clutching element which in the present 95 instance is a split, expandable ring but which as is obvious might take some other form. I combine with this clutching element a pair of levers which are mounted for swinging movement and a device for operating the 100 levers to put said clutching element into operative relation. The operating device consists preferably, though not necessarily, of a wedge and as it advances or has its operative movement it moves away from 105 said levers and so acts on the latter as to tend to align their lines of force or thrust. It is therefore evident that there is a toggle action which tends to operate said clutching element and the toggle action powerful 110 though it may be, is aided by the lever operating device the path of which is away from said levers whereas were the lever-operating device movable toward the levers during the toggling action the said toggling action 115 would be counteracted by the lateral thrust of the lever-operating element. Not only is this the case but the leverage of the two levers is actually increased as best illustrated by the diagram, Fig. 4.

When one expansion-ring is locked to its pulley or other element the other is released, and its pivoted levers then assume the position illustrated in Fig. 2. In other words the two rings are alternately expanded and 125 alternately released, as will be evident.

Changes may be made in many of the details of the invention, and the parts may be arranged in any suitable position required, without departure from the invention.

Having thus described my invention, what I claim is—

The combination, with a shaft, of a grooved and slotted sleeve secured thereto, 5 and having a reduced end, a friction-block secured in the slot of the sleeve; a pivot-screw attached to said friction-block; levers having heads grooved to fit the screw at one end, and having rounded surfaces at their 10 opposite extremities; a split-ring in engagement with the reduced end of the sleeve, and having seats for the reception of the ends of the levers; a block movable in the groove of the sleeve, and having a rib provided with a 15 head inclined on its sides, and located between the arms of the levers; complementary

clutch-surfaces loose upon the shaft, and having a circumferential flange with the inner wall of which the split-ring engages; and means for actuating the block in the 20 groove of the sleeve to cause its inclined head to move away from the fulcrum-point of the levers, and between the free ends of the arms thereof.

In testimony whereof I affix my signature 25 in presence of two witnesses, at Hartford, Ct. this 12th day of April, 1906.

BENGT M. W. HANSON.
